UNITED STATES PATENT OFFICE.

JAMES MORTIMER MEADE, OF HONEOYE, NEW YORK.

STOVEPIPE THIMBLE.

Application filed February 6, 1922. Serial No. 534,522.

To all whom it may concern:

Be it known that I, JAMES M. MEADE, a citizen of the United States, and a resident of Honeoye, in the county of Ontario and State of New York, have invented certain new and useful Improvements in Stovepipe Thimbles, of which the following is a specification.

This invention relates to an improvement 10 in stove pipe-thimbles especially adapted for use between the floor and ceiling.

The object of the invention is to provide an improved stove pipe-thimble of this character which is so constructed and organized 15 as to be absolutely fireproof and as to completely insulate the adjacent structure of the building from the stove pipe so that the building will be protected and fire will be prevented irrespective of the degree to

20 which the stove pipe may become heated.

Another object is to provide a device of this character which is of extremely simple and durable construction, reliable and safe in operation, ornamental in appearance and 25 comparatively inexpensive to manufacture.

Other objects and advantages of the invention reside in certain novel features of construction, combination and arrangement of parts which will be hereinafter more fully 30 described and particularly pointed out in the appended claims, reference being had to the accompanying drawing forming part of this application, and in which:

Figure 1 is a view in elevation, illustrating 35 the preferred embodiment of the invention; in which portions are broken away and shown in section for the sake of illustration;

Figure 2 is a plan view; and

Figure 3 is a view in transverse horizontal 40 section.

Referring to the drawing wherein for the sake of illustration is shown the preferred embodiment of the invention, it will be seen that my improved stove pipe thimble comprises in general two telescoping sections, designated generally at 10 and 11, respectively. The section 10 comprises an inner cylinder 12 and an outer cylinder 13 arranged in spaced concentric relation and constituting a 45 pair of cylinders. The cylinders 12 and 13 are maintained in spaced concentric relation by means of a plurality or set of arms 14 which may be integrally formed with the inner cylinder 12 and which are extended 50 across the space between the cylinders and

bent around and secured to the outer cylinder 13, as indicated at 14^a in Figure 1.

Similarly the section 11 comprises an inner cylinder 15 and an outer cylinder 16 maintained in spaced concentric relation with respect to the outer cylinder by means of a plurality or set of arms 17 which may be integrally formed with the inner cylinder 15 and secured to the outer cylinder 16 as in the other section. As 65 shown in Figure 1, the arms 14 are arranged at one end of the thimble and the arms 17 are arranged at the opposite ends thereof so that these arms do not interfere or obstruct the telescopic engagement of 70 the sections. It is to be understood of course that the cylinders 12 and 13 and 15 and 16 are preferably constructed of metal.

In the assembly, the inner peripheral surface of the cylinder 16 is in sliding contact 75 with the outer peripheral surface of the cylinder 13 but the cylinder 15 is spaced a substantial distance from the cylinder 12. The stove pipe which is indicated in dotted lines extends through the cylinder 12. 80

Shells of heat insulating material, designated at 18 and 19 encase the inner and outer cylinders 15 and 16 respectively of the outer telescoping section, and a shell 20 of heat insulating material encases the inner cylinder 12 of the inner telescoping section 10. 85 These shells of heat insulating material are preferably constituted by combining asbestos cement with mineral wool and the resultant product is an extremely efficient 90 nonconductor of heat.

Metallic collars, indicated at 21 and 22 are provided and are secured to the outer cylinder 13 of the inner section 10 and the outer cylinder 16 of the outer section 11, 95 respectively. These metallic collars 21 and 22 are arranged adjacent but slightly spaced from the ends of the thimble, as clearly shown in Figure 1. This disposition of the collars is important since these collars engage the floor and ceiling, respectively, and since by spacing them from the ends of the thimble they are more effectively isolated and are prevented from conducting or transmitting heat to the adjacent structure of 100 the building.

A casing of wire mesh, designated at 25, extends between the collars 21 and 22 and about the periphery of the outer section. By constituting the outer casing of wire 105

mesh the asbestos shell 19 is protected and enclosed and at the same time the disadvantages of an impervious metallic casing are avoided. Rods 26 and 27 are provided, 5 and extend longitudinally of the thimble, the ends of the rods being secured to the collars 21 and 22. When these rods are placed in position and secured to the collars 21 and 22, the sections 10 and 11 of the 10 thimble are held against relative movement and if desired adjustable and releasable means may be provided for securing the rods to the collars as for instance the rods may be threaded at their ends and nuts may 15 be provided which coat with the threaded ends and which engage the collars. If this expedient is resorted to a pair of nuts may be utilized with each end of each rod with one of the nuts engaging one side of the 20 collar and the other nut the opposite side of the collar.

In practice, the thimble may be readily adjusted or adapted for various types of stove pipes and may be readily assembled 25 therewith and with the adjacent structure of the building. When the stove pipe-thimble is assembled with the stove pipe and with the building it so insulates the pipe as to effectively prevent the building 30 from catching on fire from the stove pipe and this irrespective of the degree to which the stove pipe is heated. Moreover the arrangement is such that neither the structure nor the effectiveness of the thimble is 35 impaired by highly heating the stove pipe, the organization of the cylinders and shells together with the wire mesh casing and the arrangement of the collars 21 and 22 preventing deterioration and bringing about 40 the advantageous results above enumerated.

I claim:

1. In a stove pipe-thimble, telescoping sections, each comprising a pair of spaced and concentric cylinders, a plurality of arms 45 for maintaining the cylinders of each section in spaced and concentric relation, the arms being arranged in sets, there being one set for each of the telescoping sections, the arms of each set extending across the space between and being secured to the cylinders of its section and the arms for the cylinders of the inner section being arranged at one end of the thimble and the arms for the cylinders of the outer section being arranged at the 55 opposite end of the thimble, shells of heat insulating material encasing the cylinders of the outer telescoping section, a shell of heat insulating material encasing the inner cylinder of the inner telescoping section, collars arranged adjacent but slightly spaced from the ends of the thimble, a casing of wire mesh extending between said collars and about the periphery of the shell of heat insulating material encasing the outer cylinder 60 of the outer telescoping section, and 65 inner of the outer telescoping section, and

rods extending between said collars and secured thereto.

2. In a stove pipe-thimble, telescoping sections, each comprising a pair of spaced and concentric cylinders, shells of heat insulating material encasing the cylinders of the outer telescoping section, a shell of heat insulating material encasing the inner cylinder of the inner telescoping section, collars arranged adjacent but slightly spaced 70 from the ends of the thimble, a casing of wire mesh extending between said collars and about the periphery of the shell of heat insulating material encasing the outer cylinder of the outer telescoping section, and rods extending between said collars and secured thereto. 75

3. In a stove pipe-thimble, telescoping sections, each comprising a pair of spaced and concentric cylinders, shells of heat insulating material encasing the cylinders of the outer telescoping section, and a shell of heat insulating material encasing the inner cylinder of the inner telescoping section. 85

4. In a stove pipe-thimble, telescoping sections, each comprising a pair of spaced and concentric cylinders, shells of heat insulating material encasing the cylinders of the outer telescoping section, a shell of heat insulating material encasing the inner cylinder 95 of the inner telescoping section, collars carried by said thimble and a casing of wire mesh extending between said collars and about the periphery of the shell of heat insulating material of the outer cylinder and 100 the outer telescoping section. 90

5. In a stove-pipe thimble, telescoping sections each comprising a pair of spaced and concentric cylinders, shells of heat insulating material encasing the cylinders of the outer telescoping section, a shell of heat insulating material encasing the inner cylinder of the inner telescoping section and collars adjacent but slightly spaced from the ends of the thimble, one of said collars being 105 carried by the inner section and the other of said collars being carried by the outer section. 110

6. In a stove pipe-thimble, telescoping sections, shells of heat insulating material associated with said sections, and collars carried by said sections. 115

7. In a stove pipe-thimble, telescoping sections, shells of heat insulating material associated with said sections, collars carried by 120 said sections, and a casing of wire mesh extending between said collars and about said telescoping sections.

8. In a stove pipe-thimble, telescoping sections, each comprising a pair of spaced and 125 concentric cylinders, a plurality of arms for maintaining the cylinders of each section in spaced and concentric relation, the arms being arranged in sets, there being one set for each of the telescoping sections, the arms 130

of each set extending across the space between and being secured to the cylinders of its section, and the arms for the cylinders of the inner telescoping section being arranged at one end of the thimble and the arms for the cylinders of the outer telescoping section being arranged at the opposite end of the thimble.

5

tions adapted to embrace the stove pipe, and 10 collars carried by the sections adjacent the ends thereof and spaced from the ends at a substantial distance, said collars being engageable with the supporting structure and insulated from the sections by virtue of their 15 spaced relation with respect thereto.

9. In a stove pipe thimble, telescoping sec-
